J. B. WINSOR

METHOD OF AND APPARATUS FOR PUMPING WELLS

Filed Dec. 31, 1926

UNITED STATES PATENT OFFICE.

IRWIN B. WINSOR, OF TULSA, OKLAHOMA.

METHOD OF AND APPARATUS FOR PUMPING WELLS.

Application filed December 31, 1926. Serial No. 158,353.

My invention relates to a method of and apparatus for conducting a flow of fluid from wells and more particularly to apparatus for the employment of which the well casing may be utilized as a conduit for the overflow of the fluid.

The principal object of my invention is to provide for the support of a liner a means such as a well packer so positioned within 10 and near the lower end of a well casing that the engagement of the packer with the walls of the casing will serve to divide and seal the well into upper and lower portions.

By the use of my device the fluid which 15 is forced into the upper well portion through the liner suspended from the packer will be prevented from escaping back into the bottom of the well, and the casing of the said upper portion will serve as a conduit for the 20 outflow of the fluid, thus eliminating the tubing reliner such as is commonly used in present practice.

A further advantage of my invention resides in the suspension of the pumping apparatus from the lower end of the tubing in such manner that the same can be removed from and replaced in position in a well without disturbing the packer.

In the drawings:

30 Fig. 1 is a fragmentary sectional view of an oil well showing the apparatus applied therein.

Fig. 2 is an enlarged sectional view of the pump supporting and sealing means, and 35 the upper end of the pump.

Fig. 3 is a detail perspective view of the lower end of the pump shown in Fig. 2.

Referring in detail to the drawings:

1 designates an oil well provided with a 40 lining casing 2 which extends downward from a casing head 3 having an outlet flow line 4 and is supported on the cap rock 5 by the casing shoe 6. The cap rock 5 overlies the oil sand 7 and an oil pocket 8 within the 45 sand contains oil 9 which flows through the sand into the pocket.

A fluid pump indicated by the barrel 10 and the tubular pump rod 11 of the type illustrated in my application for patent on 50 oil well pump filed May 14, 1925, Serial No. 30,221, is suspended into the oil pocket 8 and immersed in the oil 9 for the purpose of forcing the fluid upward and out through flow line 4 which leads from the casing head

55 3. A conical head 12 is provided at the upper end of the pump barrel 10 and an ex-

ternally threaded portion 13 of the head is adapted to engage within the internally threaded upper end 14 of the barrel.

An opening 15 through the head 12 is provided for the reception of the pump rod 11 which is connected with the sucker rod 16 that extends to the top of the well and constitutes the means of joining the pump rod to actuating means (not shown) at the mouth 60 of the well. The said pump rod 11 reciprocates within the pump barrel 10 and causes the fluid to be lifted upward through the channel 17 in the pump rod 11 and out of the check valve 18 into a pump support liner 65 designated by 19, a portion of the fluid leaving the pump rod and being returned thereto before issuing from the valve 18, as will later be described.

Secured to the lower end of the liner 19 70 in a manner shown as by screw-threaded engagement, is a coupling 20 having an opening 21 of slightly less diameter than the internal diameter of the liner 19; the conical head 12 is positioned in said opening 21, the 75 tapered portion of said conical head seating in a tapered portion 22 of said opening 21 of coupling 20, the discrepancy referred to in the relative diameters of interior of the liner 19 and the opening 21 of the coupling 80 85 being provided for in order that the head 12 will have clearance when being passed through the liner as will be described. A further feature of the internal outline of coupling 20 is the cylindrical portion 23 of the opening 21 extending downwardly from the tapered portion 22 and designed for the reception of the pump barrel 10 by the coupling 20.

The upper end of the liner 19 is threaded 90 into the lower end of a well packer 24 having jaws 25 which engage the walls of the casing 2 and so enable the packer to support the liner 19 in a position near the lower end of the casing, whereby that portion of the casing above the packer is left open to the flow of oil without other obstruction than the sucker rod 16.

A screen 26 is provided depending from the barrel and attached thereto by a collar 105 27. The collar constitutes a standing valve seat for the standing valve 28 that has a beveled seat 29 for reception of the valve ball 30, the ball traveling in a sleeve 31 having a cross pin 32 for limiting the travel of 110 the ball. The sleeve has vertical grooves 33 on its inner wall through which oil may pass

around the valve ball 30 on the upstroke or sucking action of the pump rod 11 influenced by the sucker rod 16. 34 and 35 designate cups and spacers embracing the pump rod, 6 the cups suctionally engaged with the walls of the pump barrel 10. Positioned within the tubular pump rod 11 and below the said suction cups carried exteriorly by said pump rod, is a moving valve 36, comprising a collar 10 lar 37, seat 38 and valve ball 39.

Oil in annular chamber designated 40 of the barrel, pressed downward by the cups 34 in the downward functioning of the pump rod, closes standing valve 28; and at the 15 same time, the pressure on the oil in said chamber forces said oil upward to open valve 36 in the lower end of the pump rod, the valve admitting the oil, as the structure discloses, to the interior of the tubular pump 20 rod 11. The reverse or sucking action of the pump withdraws the oil in the lower part of chamber 40, thereby withdrawing valve ball 30 of standing valve 28, the said suction being transmitted to the oil in the 25 oil pocket to draw the same into the lower end of the barrel and of the valve. At the same time, the upward motion of the pump rod results in the seating of the valve ball 39 of the valve 36 whereby the pump is enabled to lift the oil contained within it upward in chamber 40 of the barrel 10.

The pump rod 11 is provided with ports 41 through which the oil, delivered as described to the channel 17 in the pump rod, is delivered from the pump rod 11 to the annular chamber 42 of the barrel above the cups 34, upon the downstroke of the pump rod, the oil being otherwise detained in said chamber by valve 36 and by the upper closure of 45 said barrel chamber by the conical head 12.

Assuming the apparatus to be constructed as described, the application and operation in a well are as follows:

The packer 24 with the liner 19 suspended 45 therefrom is lowered to the desired position in a well by such means as are commonly employed for that purpose and the packer is engaged with the walls of the casing 2 by the jaws 25 to hold the same securely in position, 50 and sealing that portion of the well casing above the packer from communication with the portion below the packer.

The pump barrel 10 is then lowered into the well suspended from the sucker rod 16 55 and passed through the packer 24, the liner 19 and through the coupling 20, the passage being facilitated by the fact above mentioned that the upper interior diameter of the coupling is less than that of the liner; 60 until the conical head 12 seats within the tapered opening 22 of the coupling. In operation a reciprocating motion is conferred on

the sucker rod 16 and the attached pump rod 11, and the fluid is forced up through the barrel 10, as above described, into the 65 liner 19. From the liner 19 the fluid is forced upward through the packer 24 into the well casing above the packer, the well casing serving as a conduit conducting the fluid to the casing head 3 from which it 70 passes off through the flow line 4 to storage tanks or the like (not shown).

What I claim and desire to secure by Letters Patent is:—

1. In combination with well casing, a 75 packer in the casing, a liner suspended from the packer and communicating with the casing above the packer, a pump barrel suspended from the liner, a standing valve in the pump barrel, a hollow pump rod in said 80 barrel connecting with the liner, a piston in said barrel having an upwardly opening valve controlling flow between the barrel and rod, an upwardly opening valve on the rod controlling flow between the rod and liner, 85 and means for operating the pump rod.

2. In combination with well casing, a pump barrel suspended from and having sealed relation with the casing, an upwardly opening valve in the pump barrel, a hollow piston in the barrel having an upwardly opening valve, a hollow rod on the piston having valved communication with the casing, and means for reciprocating said rod.

3. In combination with well casing, a 95 packer in said casing, a liner suspended from said packer, having communication with the casing and having a seat, a head in sealing relation with said seat, a pump barrel suspended from said seat, a standing valve in 100 said barrel, a hollow, valved piston in said barrel, a hollow rod for said piston, slideable in said head and having valved communication with the liner, and means for operating the rod.

4. In combination with well casing, a packer in the casing, a liner suspended from said packer, communicating with the casing above the packer and having a tapered seat, a conical head in upwardly removable sealing relation with said seat, a pump barrel suspended from said head, a hollow piston in said barrel, having an upwardly opening valve, a hollow rod for said piston, slideable 110 in said head and having an upwardly opening valve controlling communication between the rod and liner, and means for reciprocating said rod, said piston being engageable with said head upon extended upward movement of the rod to lift the head from the 115 seat.

In testimony whereof I affix my signature.

IRWIN B. WINSOR.
